Primary Examiner — Shawn T Gingrich(74) *Attorney, Agent, or Firm* — Keusey & Associates, P.C.(57) **CLAIM**

The ornamental design for a connector with locking tabs, as shown and described.

DESCRIPTION

FIG. 1 is a top, front, right side perspective view of my new design of a connector with locking tabs.

FIG. 2 is a top plan view thereof.

FIG. 3 is a right side elevational view thereof.

FIG. 4 is a bottom plan view thereof.

FIG. 5 is a left side elevational view thereof.

FIG. 6 is a front side elevational view thereof; and,

FIG. 7 is a rear side elevational view thereof.

The broken lines in FIG. 7 represent environment only, and form no part of the claimed design.

1 Claim, 3 Drawing Sheets# US D924,158 S
